UNITED STATES PATENT OFFICE.

GEORGE H. CHINNOCK, OF BROOKLYN, NEW YORK, ASSIGNOR TO THE
VOELKER LIGHT COMPANY, OF NEW JERSEY.

HOLDER FOR INCANDESCENT MANTLES.

SPECIFICATION forming part of Letters Patent No. 595,846, dated December 21, 1897.

Application filed April 20, 1897. Serial No. 632,946. (No model.)

To all whom it may concern:

Be it known that I, GEORGE H. CHINNOCK, a citizen of the United States, and a resident of the city of Brooklyn, county of Kings, State 5 of New York, have invented certain new and useful Improvements in Holders for Incandescent Mantles, of which the following is a specification.

This invention relates to improvements in 10 holders for incandescent mantles, and it is especially intended to facilitate the placing of the mantle on and its removal from the burner.

The device essentially consists in a sleeve or 15 ferrule which is adapted to fit on the burner and is provided with a vertical rod having a hook or loop at the top from which the mantle is suspended. The sleeve or ferrule with the burner, and liability of jarring and breaking the mantle in these operations is much 20 diminished. The mantle can also be placed on its rod in the manufactory and with the ferrule in the usual boxes, all ready to be put 25 on a burner without requiring any further adjustment or expert attendant to put it on and remove it from the burner.

Referring to the drawings which accompany the specification to aid the description, Figure 30 1 is an elevation of a holder with its mantle-supporting rod. Fig. 2 represents a mantle as just being put on the holder. Fig. 3 is an elevation showing the mantle in position on the holder; and Fig. 4 is a plan of the same, 35 but with the supporting-rod broken away. Fig. 5 is an elevation of the upper part of a burner and indicating the holder by dotted lines. Fig. 6 is a broken elevation on a small scale, showing the burner entire and the 40 holder in position.

The ferrule or sleeve A is shaped to fit truly but easily on the burner-head B, as indicated in Figs. 5 and 6, and is provided with a mantle-supporting rod C, which is conveniently made of a wire that is tightly turned at its 45 lower part around said ferrule A, and the lower edge of the ferrule A is then turned up over the wire C, as shown at a, thereby fastening the wire to the ferrule. At its upper end said rod C is provided with the hook c 50 to engage in the loop of asbestos or other incombustible material d, which is fixed in the usual manner on the top of the mantle D. Said hook c is so formed that the bend of the wire C rises sufficiently high to be easily 55 grasped by the user.

The rod C is cut to proper length to suit the mantle after being burned out, and a mantle may be placed on the rod in the factory and the whole shipped in the usual boxes, 60 being ready for use without further adjustment.

Now, having described my improvements, I claim as my invention—

The combination of a mantle-support C, a 65 ring on the lower end thereof, a ferrule A inserted tightly in said ring and adapted to fit removably on a burner, and the edge of said ferrule A being turned over said ring, substantially as and for the purpose described. 70

In testimony that I claim the foregoing as my invention I have signed my name, in presence of two witnesses, this 19th day of April, 1897.

GEORGE H. CHINNOCK.

Witnesses:

HENRY V. BROWN,
BERNARD J. ISECKE.
